UNITED STATES PATENT OFFICE

2,187,219

FLOOR RACK FOR REFRIGERATOR CARS

Charles D. Bonsall, Pittsburgh, Pa., assignor to
 P. H. Murphy Company, New Kensington, Pa.,
 a corporation of Pennsylvania

Application November 19, 1937, Serial No. 175,487

7 Claims. (Cl. 105—375)

The invention relates to insulated railway refrigerator cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

In a refrigerator car water ice is associated with certain elements of the car to establish a convection circulation of air between the refrigerant chamber and the lading compartment to cool the lading in the car (as hereinafter described). A foraminous floor supports the lading in spaced relation to the insulated floor of the car.

Lump ice is frequently placed on top of a perishable lading to cool it and sometimes pulverized ice is blown above and between the lading to cool it. Such ice upon melting drains to the floor of the car.

It is desirable to allow at least some of the melted ice to remain on the insulated floor of the car below the foraminous floor to produce further insulation between the outside of the car and the air flues below the foraminous floor and also to further cool the circulating air. The melted ice (water) has a temperature about 32° Fahrenheit when no salt is used and as low as 14° Fahrenheit when 25% salt is mixed with the lump ice, therefore, it can effectively perform the two above mentioned functions. Sometimes this melted ice freezes again and adheres to the foraminous floor supports, making it difficult to remove them.

An object of the invention is to provide a floor rack comprising a foraminous floor supported in spaced relation to the insulated floor of the car by a plurality of channel stringers which are so formed as to facilitate their removal from ice formed on the insulated floor.

A further object is to form the foraminous floor supports so as to minimize their resistance to the flow of circulating air by providing means for air to circulate through them.

In the drawings:

Figs. 1 and 2 show the relation of my improved floor rack to the other elements of a refrigerator car.

Figs. 3, 4 and 5 show the preferred form of my invention wherein the floor rack comprises

a perforated metallic plate supported by perforated channel shape stringers.

Fig. 6 shows a modification of the construction shown in Figs. 3, 4 and 5.

Figs. 7, 8 and 9 show a modification wherein the floor rack comprises a perforated metallic plate having depending marginal flanges engaging the floor of the car.

Figs. 10 to 16 inclusive show a modification wherein the floor rack comprises a perforated metallic plate supported by cross beams having depending feet engaging the floor of the car.

In the form of my invention illustrated the refrigerator car is provided with a bulkhead 2 separating the refrigerant chamber 3 from the lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the ice supporting means 12 in the refrigerant chamber 3 in spaced relation to the floor 6 of the car and the basket (or netting) 13 spaces the refrigerant from the end wall 14 and bulkhead 2 to provide the flues 16—17. The apertured floor rack, or 25 foraminous floor, supports the lading so as to provide the space 20 which communicates with the flues 16—17. A refrigerant, such as ice in the refrigerant chamber, induces a convection circulation of air from the flues 16—17, through 30 the flue space 20 and the apertures 21 in the floor rack, and as the air is warmed by the lading, it rises and passes through the bulkhead upper opening 7 and thence through the flues 16—17, and being cooled by the refrigerant, repeats the 35 convection cycle.

When a stove or other heater is placed in the refrigerant chamber a convection circulation of air is induced in the opposite direction because the air warmed by the heater rises and falls when 40 cooled by the lading.

Figs. 3, 4 and 5 show a floor rack comprising a metallic plate 25 provided with a plurality of apertures 21 which are supported upon the floor 6 of the car by a plurality of substantially parallel 45 channel shape stringers. The lower portions of these stringers have solid bottom (26), side (27) and end walls (28) forming a closed construction to prevent the water from the melted ice getting into the channel of the channel section where 50 it might freeze making it difficult to raise the floor rack. The side walls 27 of the channel shape stringers preferably converge toward the bottoms 26 of the stringers to facilitate their removal from ice formed on the insulated floor. 55

- The side walls 27 of the channel shape stringers are provided with apertures 30 and also the metallic plate 25 above the channel shape stringers are provided with apertures 21 so that air may move from the spaces 20 below the floor rack to the lading compartment 4 above the floor rack. Air also moves from the spaces above (4) and below (20) the floor rack, respectively, through the apertures 21 in the metallic plate 25.
- 10 The channel shape stringers are preferably positioned parallel to the movement of the circulating air. However, if the stringers extend across the direction of movement of air the apertures 30 would be made large enough not to retard such movement of air.

15 In practice the channel shape stringers are preferably made of a metallic plate pressed to the form illustrated and the ends are closed by the solid stiffeners 28 (see Fig. 5) which extend between and are secured to the opposite walls 27-27 of the channels. These members not only act as closure elements but also provide stiffeners between the opposite sides of the channel. They preferably do not extend above the bottom of the apertures 30 so as not to interfere with the movement of air lengthwise through the channel stringers. The metallic plate 25 may be welded or otherwise secured to the stringers.

20 Fig. 6 shows a modification wherein the foraminous floor comprises a perforated metallic sheet formed with upper (32) and lower (33) portions in spaced apart parallel planes connected by webs 34 with the lower portions 33 thereof resting upon and preferably secured to flanges 35 on the channel shape stringers. These flanges 35 are preferably bent upwardly between the webs 34 to engage and support the upper portions 32 of the metallic sheet, thereby strengthening them as beams and stiffeners between adjacent stringers.

25 Figs. 7, 8 and 9 show a modification wherein the floor rack comprises a perforated metallic plate 40 with depending marginal flanges 41, which flanges are rebent to form channel feet engaging the floor 6. The stiffening element 42 closes the ends of the channels to prevent melted ice from entering the channel for the purpose hereinbefore set forth. The metallic plate 40 is formed with upper (44) and lower (45) portions in substantially parallel planes connected by webs 46 with one or both of said portions being provided with apertures 47. The cross member 50 which supports the metallic plate between the marginal flanges 41 comprises a flat plate cut out for the webs 46 and lower portions 45 and extending downwardly and outwardly (51) at each end thereof and welded to one or both (52-53) side walls 54-55 of both of the marginal flanges. Such a construction offers very little resistance to movement of circulating air.

30 Figs. 10 to 14 inclusive show a modification wherein the foraminous floor comprises a metallic plate 56 formed with upper (57) and lower (58) portions in substantially parallel planes connected by webs 59. These plates are provided with marginal flanges 60 preferably secured together for cooperation therebetween. The cross beams or supports 62 comprise a metallic plate formed with channel feet 63 at each end thereof which are closed to form bucket shaped feet by the use of the element 64 shown particularly in Fig. 13. The right hand of Fig. 13 shows this element 64 omitted. Fig. 12 shows the metallic plate 56 in position to be lowered to engage the cross beams 62 shown in Fig. 13. Fig. 14 is an end view of the cross beam 62 and also shows part

of the metallic plate 56. The bucket is of closed formation and the walls thereof are tapered for the purpose heretofore set forth.

35 Figs. 15 and 16 show a modification wherein the upper flanges 70 of the stringer 71 are provided with upturned portions 72 which engage the webs 34 of the foraminous floor to resist the tendency of the foraminous floor to shift in a horizontal plane relative to the stringers, and to prevent the webs 34 from deflecting under vertical load. The flanges 70 also extend upwardly to provide a support 74 for the upper portions 32 of the foraminous floor. Both the upper portions 32 and the lower portions 33 are preferably secured to the stringer to restrain the ends 15 of the beams.

40 Figs. 15 and 16 also show a wooden 78 or other insulating member secured to the lower portion 79 of the stringer by bolts 80 to act as a heat insulation to prevent heat transfer through the 20 stringer. These wooden blocks 78 also provide means of adjusting the vertical height of the stringer. Fig. 16 is a section through line 16-16 of Fig. 15 with the foraminous floor omitted.

45 The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having an insulated floor, a foraminous floor above the insulated floor, a space between said floors and ice associated with elements of the car to induce an air current in said space upon melting thereof, said ice being positioned so that the melted ice will drain upon the insulated floor, said foraminous floor being supported upon said insulated floor by a plurality of channel shaped stringers, each comprising spaced apart side walls connected by a substantially plane web which rests upon said insulated floor, said web and the lower portion of said walls being imperforate to prevent the melted ice from entering the channel and the upper portion of the walls of each of said channel stringers being perforated for air movement from said space through the stringer to the space above the foraminous floor.

2. A structure as defined in claim 1 wherein the said side walls of the stringers converge toward the bottoms of the stringers to facilitate removal thereof from ice formed on the insulated floor.

3. In a refrigerator car having an insulated floor, a foraminous floor above the insulated floor, a space between said floors and ice associated with elements of the car to induce an air current in said space upon melting thereof, said ice being positioned so that the melted ice will drain upon the insulated floor, said foraminous floor being supported upon said insulated floor by a plurality of channel stringers with solid stiffeners extending between and secured to the opposite walls of the channels and positioned to prevent the melted ice from entering the channel, the upper portion of each of said channel stringers being perforated for air movement from said space through the stringer to the space above the foraminous floor.

4. In a refrigerator car having an insulated floor, a foraminous floor above the insulated floor, a space between said floors and ice associated with elements of the car to induce an air current in said space upon melting thereof, said ice being

positioned so that the melted ice will drain upon the insulated floor, said foraminous floor comprising a perforated metallic sheet formed with upper and lower portions in spaced apart parallel planes connected by webs, and a plurality of channel shaped stringers extending normally to said webs comprising spaced apart side walls connected by a substantially plane web which rests upon said insulated floor, and the upper portions of the side walls of the stringers being perforated.

5. In a refrigerator car having an insulated floor, a foraminous floor above the insulated floor, a space between said floors and ice associated with elements of the car to induce an air current in said space upon melting thereof, said ice being positioned so that the melted ice will drain upon the insulated floor, said foraminous floor comprising a perforated metallic sheet formed with upper and lower portions in spaced apart parallel planes connected by substantially vertical webs, and a plurality of channel shaped stringers extending normally to said webs, said channel stringers provided with horizontal flanges which are substantially sinuous to support and are secured to both of the upper and lower portions of said metallic sheet.

6. In a refrigerator car having an insulated floor, a foraminous floor above the insulated floor, a space between said floors and a refrigerant

associated with elements of the car to induce an air current in said space upon melting thereof, said foraminous floor comprising a perforated metallic sheet formed with upper and lower portions in spaced apart parallel planes connected by substantially vertical webs and a plurality of channel shaped stringers extending normally to said webs, said channel stringers provided with horizontal flanges provided with substantially vertical upturned portions engaging said webs to resist the tendency of the foraminous floor to move in a horizontal plane.

7. In a refrigerator car having an insulated floor, a foraminous floor above the insulated floor, a space between said floors and a refrigerant associated with elements of the car to induce an air current in said space upon melting thereof, said foraminous floor comprising a perforated metallic sheet formed with upper and lower portions in spaced apart parallel planes connected by substantially vertical webs and a plurality of channel shaped stringers extending normally to said webs, said channel stringers provided with horizontal flanges provided with substantially vertical upturned portions engaging said webs to resist the tendency of the foraminous floor to move in a horizontal plane, said flanges also formed to support said upper portions.

CHARLES D. BONSALL.

CERTIFICATE OF CORRECTION.

Patent No. 2,187,219.

January 16, 1940.

CHARLES D. BONSALL.

It is hereby certified that the above numbered patent was erroneously issued to P. H. Murphy Company, of New Kensington, Pennsylvania, a corporation of Pennsylvania, whereas said patent should have been issued to Standard Railway Equipment Manufacturing Company, a corporation of Delaware, as assignee by mesne assignments of the entire interest therein, as shown by the record of assignments in this office; and that the said Letters Patent should be read with this correction therein that the same may conform to the record of the case in the Patent Office.

Signed and sealed this 12th day of March, A. D. 1940.

Henry Van Arsdale,
Acting Commissioner of Patents.
